UNITED STATES PATENT OFFICE

2,002,271

KNITTED FABRIC

Vincent Lombardi, Garden City, N. Y.

Application October 18, 1933, Serial No. 694,042

8 Claims. (Cl. 66—169)

This invention relates to knitted fabrics particularly of the type employing yarn of different characteristics in producing pattern effects and wherein certain yarns in certain portions of the fabric are concealed behind loops of other yarn. An object is to provide improved and novel pattern effects and in certain embodiments to provide pattern effects on the rear side of the fabric suitable to be used as the exposed side of a garment manufactured therefrom.

As to another important feature it may be noted that while the interlock fabric of U. S. Patent #1,426,576 issued Aug. 22, 1922, is satisfactory for a two color fabric, it is generally unsatisfactory for three or more color knitting because of undue thickness and operating difficulties in its production on a single row of needles. A particular object of this invention is to provide a three or more color fabric comparatively thin, capable of being produced on a single row of needles, and having each color yarn form blocks or stripes of jersey stitch with the other color yarns concealed in the rear thereof, until a wale is reached where another color yarn comes to the front for forming jersey stitches, thereby producing a fabric of three or more colors in which each portion is distinctly a definite desired color without having the front color mixed in with colors of yarns forming loops in other portions. It is contemplated that the same effect may be desirable for three or more yarns of any differing characteristic or for that matter all yarns may be identical.

The general principle of the invention is to have one or more successively fed yarns to form loops in contiguous wales and rows and in the portion so formed to pass subsequently fed yarns loosely behind said wales; and then to have said loose yarns in turn form regular loops in a plurality of contiguous wales and rows with yarns normally knitting in said first portion passing loosely behind the loops in the second portion. If desired there may be a wale between said two portions where all yarns knit to produce a firmer connection between the two portions. It may also be desirable in one or more wales of one portion to tie in one or a plurality of the loose yarns, as by interlocking for example, between two loops in adjacent rows. Such a bunching of the loose yarns when applied at various points in the fabric produces an embroidery effect which renders the reverse side of the fabric desirable as the exposed side in garment manufacture. Other features of the invention will appear in the following detailed description.

The invention will be better understood by reference to the following detailed description taken in connection with the accompanying drawings in which

Fig. 1 represents schematically the reverse of a two color fabric where each color is fed singly; 5

Fig. 2 is an edge view of the fabric of Fig. 1;

Fig. 3 is the schematic of a three color fabric, reverse side, knitting one at a time and in rotation; 10

Fig. 4 is the schematic, reverse side, of a two color fabric similar to Fig. 1 except two yarns of each color alternate with two yarns of the other color;

Fig. 5 is similar to Fig. 4 except that each color 15 knits four yarns before the feeding of the other color yarn and shows the general appearance of the fabric;

Fig. 6 is the general appearance of the reverse side of a fabric as in Fig. 5 where several yarns 20 of one color alternate with a corresponding number of the other color;

Fig. 7 gives the front appearance of the fabric of Fig. 6;

Fig. 8 is the schematic, reverse side, of a fabric 25 similar to Fig. 4 except the yarns of only one color skip the formation of loops to give the loose yarns previously mentioned;

Fig. 9 is the general appearance of Fig. 8, reverse side, showing the bulging or puffing towards the front due to yarns of only one color 30 skipping the formation of loops;

Fig. 10 is the same as Fig. 9 except it shows the front side of the fabric;

Fig. 11 is an edge on view of Fig. 10;

Fig. 12 is similar to Fig. 5 except that all yarns form loops in a wale between the two looped portions of different colors;

Fig. 13 is the general appearance of the front of Fig. 12;

Fig. 14A is the schematic of a four color fabric, reverse side, with the four colors knitting one at a time, and forming the aforementioned loose yarns;

Fig. 14B is similar to Fig. 14A except that the 45 loose yarns are periodically interlocked in wales of the yarn loops behind which they lie;

Fig. 15 is a detail of the interlock feature of Fig. 14B;

Fig. 16 is the general appearance of the reverse 50 of a fabric as in Fig. 6 except having the loose yarns tied-in as in Fig. 14B;

Fig. 17 is the schematic of the rear of a fabric somewhat like Fig. 6 but with the loose yarn portions staggered on diagonals instead of vertically 55

- and horizontally and with the loose yarns tied in as in Fig. 15;
- Fig. 18 is the general appearance of a fabric as Fig. 17, also the rear view;
- 5 Fig. 19 shows the peculiar type of bias produced with a group of yarns knitting throughout the fabric alternating with groups of yarns alternately looping and forming loose yarns, in staggered wales the said loose yarns being tied as in Fig. 15 the reverse side of the fabric being shown;
- 10 Fig. 20 is the general appearance of a fabric as in Fig. 19, also reverse side;
- Fig. 21 is the front view of a four color fabric like that of Fig. 14B;
- 15 Fig. 22 is the front view of a two color fabric, each color four wales wide;
- Fig. 23 illustrates various possible treatments of the yarn bundles on the rear of the fabric;
- 20 Fig. 24 is an alternative to the arrangements of Fig. 23 and a further development of a part of Fig. 23;
- Fig. 25 represents how the rear yarn bundles may be treated to form pleats in the front of the fabric;
- 25 Fig. 26 is an edge view of the fabric of Fig. 25;
- Fig. 27 represents schematically various choices of wales in which the loose yarns may be tied in certain fabrics of this invention; and
- Figs. 28 and 29 show modified fabrics.
- 30 Referring particularly to Fig. 1 the schematic form of the reverse side of a knitted fabric shown therein illustrates a form of pattern in which yarns of two colors are employed, each yarn knitting alternately in several successive rows, the alternate yarns being of one color and the remaining yarns of a different color. Thus yarns 30, 32, 34, 36, 38 are of one color and yarns 31, 33, 35, 37 of a different color. Yarn 30 forms loops in eight successive wales from wale 39 to wale 40, then passes to the rear of the fabric where it follows an unlooped path for eight wales from wale 41 to wale 42 where it lies behind the loops of a previously fed yarn 31 which is of the other color. After wale 42, yarn 30 begins looping again and forms regular loops in six wales ending the section A. In section B all yarns form loops so that section B when viewed from the front is a mixture of the two colors. It is apparent that section C is a repetition of section A. Yarn 31 between wales 39 and 40 lies behind the loops of yarn 32, forms loops in wales 41 to 42 and lies behind the loops of yarn 32 in wales 43 to 44. The path for each of the yarns 32, 34, 36 and 38 is the same as for yarn 30 while the path for each of the yarns 33, 35, and 37 is the same as for yarn 31. Thus the front of the fabric between wales 39 and 40 and between wales 43 and 44 will be of the color of yarn 30, while in wales 41 to 42 the color will be that of yarn 31. In each part of section A there is yarn passing behind each series of loops of the other color. This arrangement therefore forms wide vertical stripes of alternate colors in the fabric, that is stripes running at right angles to the direction each yarn is fed to the needles. Furthermore there is no chance for any yarn lying behind regular loops to show through the fabric when viewed from the front. The feature of Fig. 1 is therefore that yarns of each color form loops in several successive wales and then for several wales pass behind several successive wales of loops of yarn of the other color. Another important feature is having the long unlooped portion of each yarn lie behind loops of a previously fed yarn, as in Fig. 1 the knitting is from bottom to top. The loops in section B are shown smaller than the size of those in section A, but the showing in this figure as in other schematic views such as Figs. 3 and 4 does not necessarily show the true relative loop sizes as in reality the various loops will tend to be of the same size, tending to pucker the fabric which may later be pressed out.
- 5 Fig. 2 is an edge view of the fabric of Fig. 1, the dotted portions representing loops in the front of the fabric and the long straight lines representing the unlooped lengths of each color yarn lying behind loops of the other yarn color. Thus we may assume that the figure traces the paths for yarns 30 and 31.
- Fig. 3 applies the principles of Fig. 1 to a 15 three color fabric. Thus yarn 45 of one color at the left of the figure forms loops in eight successive wales, then is passed to the rear of the fabric where it extends in a substantially straight path behind eight successive wales of loops of 20 a previously fed yarn 46 of a second color, then continues in the rear of the fabric for eight more wales of loops of a previously fed yarn 47 of the third color, after which yarn 45 again forms loops in the front of the fabric for a desired number of wales, repeating if desired the pattern effect just described. Thus each color yarn forms loops for a desired number of wales then passes to the rear of the fabric where it lies in a substantially straight path behind loops 30 of the other two yarns of different colors without being caught in the knitting along said path until it again begins to form loops in the front of the fabric. It will be apparent therefore that each series of loops of yarn of one 35 color has behind the loops a straight portion of yarn of the second color and a straight portion of yarn of the third color. Yarns 48 and 51 are of the same color as yarn 45 and follow similar paths; yarn 49 is of the same color as yarn 40 46 and follows a similar path; and yarn 50 is the same color as yarn 47 and follows a similar path. Thus in Fig. 3 every third fed yarn is of the same color. The view of Fig. 3 is of course schematic and taken from the rear the normal 45 fabric would be more tightly knitted. It will be apparent that the front of the fabric will have solid vertical stripes of the three different colors, each eight wales wide or any other desired width, and each stripe viewed from the front will not 50 disclose the yarn of the other colors.
- Fig. 4 is also a schematic showing but in this case two yarns of each color are fed in succession followed by two successively fed yarns of the second color and then repeating. Thus yarns 55 52, 53 are of the same color and each forms loops in six wales from wale 54 to wale 55, the loops of yarn 52 being shown the larger, although in the actual fabric the knitting will result in loops of all about the same size, see Figure 5. The two 60 yarns 54, 55 then pass to the rear of the fabric where they both lie behind a row of loops of yarn 56 which is of a different color, after which they begin the formation of regular loops. Yarn 56, 57 of a color differing from yarn 52 lie together 65 behind the row of loops of yarn 58 from wale 54 to wale 55, there form loops in the next six wales and repeat the process. Yarn 52, 53, 58, 59, 62, and 63 are of one color while yarns 56, 57, 60, and 61 are of the second color. The front appearance 70 is substantially the same as in Fig. 1 namely solid vertical stripes of the two colors.
- Fig. 5 is an extension of the feature of Fig. 4 except that four successively fed yarns are of the same color. Fig. 5 also as in previous figures 75

shows the reverse of the fabric but instead of being schematic it shows the natural distribution of the fabric resulting from the particular type of knitting shown therein. In section D the loops 5 are all substantially the same size and are all of the same color. In section E all of the loops are of a second color. Each group of four yarns of the first color forming loops in section D are bunched in parallel paths behind the loops in 10 section E; while each group of four yarns of the second color are bunched in parallel paths behind the loops in section D. The transition from section D to section E gives a marked characteristic in the front of the fabric as each group 15 of yarns ceases forming loops and retires to the back of the fabric and vice versa. The loose yarns from right side of section E are shown broken off to show uniform knitting to the right of section E.

20 Fig. 6 shows the general appearance of the rear of a fabric made in accordance with Fig. 5 each color group consisting of any number of yarns as many as eight for example. Section F Fig. 6 represents all loops of the first color and periodically on the back thereof are bunched the group of yarns eight for example which do not form loops in section F but do in section G. The next section to the right of section G, is the same as section F, the next the same as 25 section G, etc. For example the parallel yarns eight for example in group 70 form loops in sections F and H but in section G lie behind the loops of yarn of the other color. The peculiar 30 tucking effect at the junction of sections F and G should be noted as it forms an important characteristic of pattern effect of this invention.

Figure 7 shows in perspective the appearance of the front of a fabric made in accordance with Fig. 5. Section F is composed of loops of all the same color, the same as section H, while section 40 G is a solid stripe of a different color. In having eight for example successively fed yarns form loops say in section F and then have all eight pass to the rear of loops in section G of yarn which was in the rear of section F gives a unique 45 pattern effect where each group of eight is tucked in under the regularly formed loops of the other color. Note that for example the edges of section F at the points 71 to 74 are not directly looped in with the loops of the yarns in adjacent sections but merely lie on top of the other color 50 yarns which are passing to the rear at the designated points. That is, the loops in the last wale formed in section F (refer also to Fig. 5) 55 are not interlooped with the loops in the first wale formed in section G, so that loose edges are formed along the sides of each stripe but not in such a manner as to permit unraveling or destruction of the fabric.

60 Figs. 8, 9, 10, and 11 illustrate another type of pattern effect that may be produced in accordance with this invention. In Fig. 8 the rear of a two color fabric is schematically disclosed in which yarns of only one color skip the formation 65 of loops as in Fig. 1. Thus yarns 80 to 86 are of one color and all the other yarns are of a second color. Thus beginning at the left yarns 80 to 84 lie behind loops in several wales of loops of the second color then form loops in the regular 70 manner between wales 87 and 88, and then repeat the cycle by passing behind the loops of the second color for several wales, etc. It should be emphasized that Fig. 8 is schematic only to show the character of the knitting. Actually the 75 fabric of Fig. 8, will look quite different because

of the fact that the periodic failure of the yarns of one color to form loops is not compensated for by corresponding unlooped portions of the second color. This results in a pinching or a bulging of the blocks of loops of yarns 80 to 84 away from the average surface of the fabric. This crowding and consequent bulging of the loops of yarns 80 to 84 is shown more clearly in Fig. 9 which shows the actual distortion of the fabric of Fig. 8 also viewed from the rear. In 10 the upper central portion of Fig. 9 will be seen the resulting crowding of the loops of yarns 80 to 84 causing them to project away from the front of the fabric as a block color upon a background 15 of the second color. These projecting bulges may of course be distributed throughout the fabric to create any desired pattern effect. Thus Fig. 10 represents a front view of such a fabric as that of Fig. 9 where each shaded block such as block 20 90 is an outwardly bulging portion say of black on a background of the yarn of the other color, white for example. A side view of the fabric of Fig. 10 is shown in Fig. 11 where the bulges above 25 the level of the main fabric are shown at the left of the figure, such as at points 91, 92.

It has been pointed out above in connection with Fig. 5 the loose connection between adjacent sections such as sections D and E, due to the fact that the loops in the last wale of D are of one 30 color yarn only, while all the loops in the first wale of section E are of the other color yarn exclusively. If desired an improved connecting link between such sections can be provided by having a wale between sections D and E where 35 all yarns of both colors knit regular loops. This is exemplified in Fig. 12 where section M is composed exclusively of loops of one color yarn, section N composed exclusively of loops of the second color yarn, the second color yarn, lying in bunched parallel paths in the rear of section 40 M and the first color yarns lying in bunched parallel paths in the rear of section N, much as in Fig. 5 except that between sections M and N there is a wale 94 where yarns of both colors knit in succession to provide a more binding connection 45 between the two sections. The view in Fig. 12 is of course of the rear of the fabric. A front view of the fabric of Fig. 12 is shown in Fig. 13 which gives the general appearance. Sections O and Q are of one color and sections P and R of 50 a second color. The general appearance is different from Fig. 6, giving a ragged edge toward other sections with an interlocking effect like gearing.

Fig. 14 section A is a rear view schematically 55 shown of a fabric not substantially different from that described above except that it is four color knitting, one at a time, in rotation. Thus yarns 95 to 98 are of different colors, each forming a row of loops and then lying in a substantially 60 straight path behind loops of the other color yarns unattached to the fabric of the said other color yarns in its rearward path, each yarn being taken up in the knitting only in the wales where it forms regular loops.

In Fig. 14 section B a new feature is introduced 65 in the knitting. The transition between sections A and B Fig. 14 is not fully disclosed as section B may be treated as a separate fabric. Fig. 14 section B is also of four color knitting one at a 70 time and in rotation. For simplicity let us designate by one character all yarns in this section of the same color. Portion a comprises loops entirely of yarn 100; portion b by entirely yarn 101; portion c entirely yarn 102; and portion d 75

entirely yarn 103; said four yarns being of different colors. In the middle wale of portion *b* the loops of yarn 101 have periodically interlocked therein in the rear of the fabric the three adjacent 5 cent yarns 100, 102, and 103 of the other three colors. Thus at the point 104 after the formation of the loop 105 of yarn 101 the next three yarns fed of the three other colors are caught on the needle which formed loop 105 but without knitting the same and when the next fed color yarn 101 comes around the said three unlooped yarns fall below the needle latch, loop 106 is formed and as a result the said three yarns are interlocked between loops 105 and 106 in the manner 10 15 described in my U. S. Patent #1,426,576 issued Aug. 22, 1922. The other interlocking points in section B are made in the same manner. It should be noted that in this figure the only interlocking of the unlooped yarns takes place in the middle 20 wale of each color stripe but the interlocking can take place in any desired wale. Since the interlocking in each portion takes place between loops of successively fed yarns it follows that the corresponding interlocking points of portions *a*, 25 *b*, *c*, and *d* are not on a horizontal line but on a diagonal. It should also be remembered that section B Fig. 14 is schematic but the actual details of the knitting would be as shown in Fig. 15 which is an enlarged reproduction of point 104 30 of Fig. 14. Further description of Fig. 15 is believed unnecessary, except to emphasize that Fig. 14B is the same fabric as Fig. 14A save for the interlocking and consequent bunching of the loose 35 yarns, also it is not necessary to interlock the loose yarns in every section.

The general appearance of a fabric such as shown in Fig. 6 when modified to have the loose 40 yarns tied or interlocked one or more times in the rear of each colored stripe is shown in Fig. 16. Such a fabric has desirable pattern characteristics on its reverse side so that it frequently 45 is desirable to use the reverse side of such a fabric as the exposed side of a garment made thereof. It will be obvious from the foregoing that points 50 such as 110 in Fig. 16 represents tying or interlocking points for the loose yarns as illustrated in Fig. 15.

Now let us assume a single color fabric in which 55 at definite but irregular intervals six yarns are unlooped behind loops of other yarns for several wales the said six yarns being caught in an interlocking manner at one or more points in each unlooped portion. The reverse side of such a fabric is shown schematically in Fig. 17. Thus the 60 six yarns from yarn 111 to 112 are not regularly looped between wales 113 and 114 but lie in the rear of the fabric behind the loops of the yarn fed previously to yarn 111. In each of the wales 115 and 116 the said six loose yarns are tied or interlocked in the manner of Fig. 15 between the loop 65 of the yarn fed previously to yarn 111 and the loop of the yarn fed subsequently to yarn 112. In the lower portion of Fig. 17 the loose yarn sections and the tying-in points for the loose yarns 70 are staggered with respect to the corresponding parts just described. Thus in wale 114 at the point 119 six loose yarns are tied in which yarns do not form loops between wales 117 and 118. Still farther down and to the right six other loose 75 yarns are similarly interlocked at the point 120 in wale 118. Another tying-in point for six loose yarns is shown at point 121. Thus the sections of the fabric having loose yarns can be staggered in accordance with a preconceived pattern which will be correspondingly followed by the tying-in

points. One type of such a pattern effect is shown in Fig. 18 where the loose yarns extending over a variable number of wales are shown in relief on the white background which is assumed to be the regularly looped portion of the fabric. It is of course understood that one may use on the outside of a garment manufactured in accordance with Fig. 18 the side having the loose yarns. The general effect of such a pattern is similar to hand embroidery work superimposed upon a knitted 10 fabric. It will be obvious that the features of Fig. 17 and 18 can be carried out with yarn of more than one color where for example the loose 15 yarns are all of the same color on a knitted fabric of a contrasting fabric or the various bunches of 20 loose yarns may be of different colors as may be desired. It is to be understood that in the actual fabric the paths of the loose yarns would be straighter than in the schematic showing of Fig. 25 20 between wales 113 and 114.

However there is a peculiar and desirable distortion when the features of Fig. 17 are applied to a fabric in which a group of successively fed yarns of one color alternate with a group of successively fed yarns of a second color when the wales for 25 the loose yarn portions in one direction are staggered. We have this exemplified in Fig. 19 where each group of one color consists of four yarns and each group of the other color has two yarns. This results in an exaggerated slanting effect mentioned in connection with Fig. 14 second B. The character of the slanting effect in Fig. 19 will be understood by noting that between the blocks A and D of the same color one will find ten wales while between blocks B and C there are only 30 four wales;—hence the slanting effect illustrated. In Fig. 19 the heavy yarns may be of one color and the lightly drawn lines may represent 35 yarns of a second color. Each looped portion of a single color when considered across the fabric slopes upwardly from left to right and then the unlooped portions of said single color slope downwardly until they begin to form loops again when they start another upward slope. In the particular portion of the fabric shown in Fig. 19 only 40 the heavy yarns have unlooped portions, the lightly drawn yarns looping in all wales. Thus 45 yarns 125 to 128 beginning at the left of the figure form regular loops in eight successive wales and then pass to the rear of the fabric where they are 50 unlooped for ten successive wales between wales 129 and 130, loosely lying on the rear of the fabric except in wale 131 where the said four yarns are tied in or interlocked between loops of the other 55 color yarn as shown in detail in Fig. 15. The other groups of four yarns are also unlooped in a slightly different series of wales so that the portions of the fabric containing unlooped yarns of the color of yarn 125 form a stripe which is not vertical but inclined to the right as one proceeds 60 downwardly from the top of the figure. The general appearance of a fabric made in accordance with Fig. 19 is shown in Fig. 20. The tucked-in 65 groups of loose yarns form a slanting configuration from top to bottom, while the stripes across the fabric between the loose yarn portions are also in a slanting path. It is obvious that the 70 number of yarns in each stripe shown in Fig. 20 may be any desired number and may vary in different portions of the fabric if desired.

As noted most of the figures described show the rear of the fabric. Fig. 21 however is a showing of the front of a fabric wherein there is a lengthwise striping effect in four colors knitted one at a time in rotation, making four loops in 75

each stripe. The loose crossing in the back appears recessed between the stripes and may or may not be tied in the back as in Fig. 15. Thus stripes 140 to 143 may each be of different color, 5 each four wales wide and each stripe having the other color yarns lying loosely in the rear of the fabric as in previous figures. Stripe 144 10 may be a repetition of stripe 140 as to color. Intermediate the stripes may be seen the loose 15 crossing yarns in the rear of the fabric as at the point 145. The effect to be noted is the definite spacing between the last wale in one stripe and the first wale in the next stripe produced by the fact as previously explained that the loops of 20 the said two wales are not interknitted but each acts as the termination of the fabric in that particular region. That is the loops in one stripe are not tied into the loops of the adjacent stripe.

Fig. 22 is the front appearance of another 25 fabric forming one type of this invention with lengthwise stripes say of two colors fed alternately six rows at a time, each yarn knitting from wales in each stripe. Thus stripes 150, 151, 30 may be of one color and stripes 152, 153 of a second color, each stripe four wales wide. The yarns forming loops in stripe 150 lie in the rear of the fabric until they form loops in the first wale in stripe 151, the same thing being true for the 35 yarns of the other stripes. The amount of un-looped yarn between stripes of the same color is sufficient to produce a definite spacing between adjacent stripes of different colors as shown in the figure. Between adjacent stripes are seen the loose 40 yarns in the rear of the fabric and in this particular figure each set of six yarns forming loops in stripes 150, 151 is tied in the first and last wales of each of the stripes 152, 153 in the manner shown in Fig. 15 and each set of six yarns forming loops in stripes 152, 153 is tied in the first 45 and last wales of each of stripes 150, 151. If the regular looping is done loosely to form a flimsy material the tying-in points may show through the fabric slightly when viewed from the front as is evident in the figure.

Figures 23, 24, and 25 show special treatment 50 of the loose yarn bundles on the rear of the fabric to create a variety of desirable pattern effects bearing in mind that the rear of the fabric may be the exposed side in garment manufactured therefrom.

Fig. 23 schematically represents the rear of a two color fabric when one color yarn knits in every wale several rows at a time and where the second color yarn knits for several wales and then forms loose yarns on the back of the fabric. 55 The lightly shaded portion of this figure such as portion 160 represents loops of one color yarn, while the blocks such as block 161 represents loops of the second color yarn in a plurality of rows and wales. The second color yarn forms loose crossing yarns between adjacent blocks as the group of yarns 162 lying in the rear of loops of the first color yarn. This group 162 is tied into loops of the first yarn in the same manner 60 as in Fig. 15 except in a row of loops formed several rows later than the row of loops of the first yarn that immediately follows the last fed yarn of group 162. The tying-in point for this group is at the point 163.

Another group 164 of the loose yarns of the second color yarn is tied-in twice in a much later 70 row of the first yarn loops as at the points 165, 166. Still another group 167 of the loose yarns of the second color is not only tied into loops of the first yarn at points 169, 170 in a subsequent

row and in wales between the blocks of loops 183, 184 of the first yarn, but the said group after forming loops in block 184 is bent back to be tied into loops of the first yarn at the point 168 in a wale corresponding to a wale of block 184. This tends to accentuate the separation between the last wale of loops in block 184 and the first wale of loops of the first yarn so as to leave a hole in the fabric at the point 179, the hole constituting a part of the pattern effect.

Still another group 171 of loose yarns in Fig. 23 between loop blocks 185, 186 is not only tied into the loops of the other color (see Fig. 15) in wales between blocks 185 and 186 but is also bent back to be tied into the fabric in a row above block 185 and in a row above block 186, thereby forming two holes in the fabric at the points 180, 181 in the manner previously described. Still another type of pattern effect is shown in connection with the groups 176, 177 of loose yarns in 20 which the group 176 is not tied into the fabric of the first color yarn but group 177 is tied in at the point 178 in a row of the first color yarn formed after the knitting of the loop rows connected by loose yarns 176 and the group 177 in 25 reaching the tying-in point pass to the rear of loose yarns 176. The various effects shown in Fig. 23 may be used in the same or different fabrics.

Fig. 24 is an enlarged detail of a modification 30 of Fig. 23 with respect to the manner in which the loose yarns are tied into the fabric and in particular it is a modification of the arrangement of groups 176, 177 of that figure. The white background in Fig. 24 is the looped fabric proper and includes both color yarn as in Fig. 23. As in all figures the lowermost part represents the first formed portion of the fabric. Group 190 may be the upper part of loose yarns tied into the first yarn loops at two separated points 191, 40 192 in a subsequent row much as in group 164 Fig. 23. The next group 193 of the loose yarns of the second color before being tied in are pulled through the loop formed by group 190 so that group 193 passes to the rear of the upper section 45 of group 190 and then is tied into the first color loops at points 194, 195. Similarly group 196 passes through the loop formed by group 193 and then is tied into the fabric and so on for the rest of the fabric. Group 197 however is 50 not tied into the fabric at an intermediate point and therefore resembles group 176, Fig. 23 although if the fabric were continued it will be readily apparent that group 197 could be pulled through loop 198 and fastened in the same manner as the others.

In Figs. 23 and 24 it is to be noted that the bundles of yarns in the rear of the fabric such as group 164 Fig. 23 are loose enough, that is the yarns are of sufficient length not to pull 60 the looped fabric together or to pinch it by reason of the irregular path taken by the groups because of the points chosen for their tying-in points.

However in Fig. 25 the loose yarns for one color yarn are restricted in length so as to pinch the looped portion in front of them. Another difference is that in Figs. 23 and 24 only one color yarn forms the bundles of loose yarns while in Fig. 25 both color yarns produce the loose 65 yarn bundles.

Referring now to Fig. 25 the rear of the fabric shown therein is of two colors in which both colors in the left hand portion form loose yarns, one color yarn with sufficient length not to pinch 70

the fabric but for the other color the loose yarns are short enough to pinch the fabric, although the illustrated loop formation is the primary cause of the bulging disclosed. Thus the groups 5 such as 200, 201 are like the bundles in Fig. 16, substantially straight, tied in at two points in the loops of the second color yarn. Each bundle 200, 201 comprises several yarns, six or eight for example and these bundles are of sufficient length 10 that they do not pinch the looped fabric in front of them. The bundles at the left such as bundle 205 are of the same color. The yarns which are in loose bundles in section 202 form regular loops in the front of the fabric in sections 203 15 and 204, but the regular loop wales in these two sections are pinched together so as to form pleats or vertical ridges in the front of the fabric separated by valleys. Thus in section 203 the yarns which form regular loops in sections 202, 206 are 20 unlooped in the ordinary sense and form interconnected bundles of yarns such as bundle 211 in the same manner as in Fig. 24 except that each bundle may be tied into the front regular loops in only one point. Each bundle in section 203 25 is tied in a row considerably above its normal position giving a loop formation so that the pulling up of each bundle to its intermediate interlocking point causes the regularly looped portion to bulge out as shown in Fig. 26 (a cross-section of Fig. 25) where portion 210 is the regularly looped but bowed out portion of section 203 (Fig. 25 and character 211 represents one 30 of the loose yarn bundles of that section. Section 204 is similar to section 203 except that both 35 color yarns form in turn a vertical row of loose yarn bundle loops as in section 203. That is the row 215 of loose bundle loops is made up of yarn which forms the regular front loops in section 202 while the regular front loops in front 40 of bundles 215 is yarn which form bundles 201, etc. in section 202. The two color yarns are in reverse position in row 216, row 217 is the same as row 215, and so on. Thus in front of the fabric of Fig. 25 we have vertical pleats of jersey 45 stitches separated by flat jersey portions such as section 202 when desired. In the rear of the fabric the loose yarns may form substantially straight bundles as in section 202 or they may be interconnected to form a chain of loops of the 50 yarn bundles as in Fig. 24 except pinching the fabric to form the pleats. The arrangement of Fig. 25 may of course be applied equally well to more than two color yarns.

Certain principles should be emphasized in the 55 disposition of the loose yarns in the rear of the fabric. Let us assume for illustration a four color fabric where the colors are fed successively one at a time to form vertical stripes of the four colors, each stripe say of six wales, and where 60 no attempt is made to bundle the loose yarns in any section. In the section therefore of the first color, the second color will pass to the rear of six wales and the question can be raised as to in how many wales and what wales the second color should be tied in as in Fig. 17. In general 65 it is preferred not to skip more than three wales before tying in the loose second color yarn and an attractive effect can be obtained by skipping 70 three wales, then tying-in in two or three successive wales, then lying loose behind the next three wales and so on until the wale is reached where the second yarn begins forming front loops. That is, it is definitely contemplated 75 that it will be frequently desirable to tie in the

loose yarns in two or more contiguous wales. The observations made above about the second color yarn will apply of course to the other color yarns of the fabric.

The above principles are exemplified in Fig. 27 5 which represents diagrammatically the various types of tying-in that may be used say in a four color fabric. Section 220 may represent a stripe of the first color six wales wide, while section 221 10 may represent a similar six wale stripe of a second color, the two stripes being slightly spaced apart as explained in connection with Fig. 21. The stripes of the other two colors are not shown but may be assumed to be the same. The horizontal lines across the wales do not represent all 15 of the loose yarns in the back of the fabric but each is intended to represent a color yarn which does not form regular loops in either section 220 or 221 and the said lines are intended to represent alternative ways of tying in the loose yarn 20 in wales of each stripe. Thus yarn 222 is interlocked in the fourth wale of section 220 and also in the fourth wale of section 221. This method will not always be desirable as one will note that the yarn is untied in five successive wales, two 25 in section 220 and the first three in section 221. The interlocking of yarn 223 is more advantageous being tied to the fabric in fourth and sixth wales of both sections. Yarn 224 is tied in the first 30 and fifth wales of both sections; yarn 225 is interlocked in the last three wales of both sections; and yarn 226 is tied in the last two wales 35 of both sections. Note that it will be occasionally desirable to interlock the loose yarn in two or more successive wales of the same row. The interlocking for yarns 222 and 226 are the least desirable of those shown since they skip more than three wales between tying-in points. It will be obvious how the principles disclosed in Fig. 27 40 may be embodied in the various types of fabric previously described.

While this invention is directed to the fabric rather than to its method of manufacture it is thought advisable to refer in general terms to the needle manipulation required to produce this 45 invention, although such will be apparent to those skilled in the art by reference to the drawings and foregoing description. Thus let us assume a row of needles all holding loops in retracted position and, proceeding in the direction of the 50 movement of a yarn carrier, groups of needles are separated out from other groups of needles in accordance with a prearranged pattern, the separated groups raised to full advanced position and the other groups left fully retracted. The 55 yarn carrier passes and the needles in the separated groups knit; but the yarn passes in a straight path over the retracted groups of needles. In a well known manner, as by sinkers, these loops and the straight yarn are pushed back with the 60 fabric to thereafter permit any needle or groups of needles to be advanced.

Thus in case the yarn in the next yarn carrier is to repeat the pattern just set up on the needles the same groups of needles will be separated out 65 and caused to knit another row of loops, and the yarn will again pass over the retracted needles, which still retain the original loops. This may be repeated a number of times, and while the loops continue to form in the selected and 70 separated groups, the loose yarns over the continuously retracted groups will be crowded together between the fabric held by these groups and the sinkers to form bundles. After say four or six yarns have been thus bundled and by the 75

sinkers are being pushed back over the top of the needle cylinder and when all needles have been fully retracted, the formerly continuously retracted groups of needles, (or parts of them, according to the prearranged pattern setting) 5 may now be separated out and advanced in front of the bundles to receive the next yarn and cause it to form loops with the original loops retained by these needles until now, this knitting continuing the fabric formerly produced by these groups in a uniform manner as far as the front of the fabric is concerned; and this knitting may be further continued without disturbance from the loose yarns on the back of the fabric which 10 now have passed over the top of the needle cylinder. During this procedure the formerly selected groups may of course be held in fully retracted position to permit the formation of bundles of loose yarns, or they partake in the knitting, so that all needles will be producing straight 15 jersey cloth.

When it is desired to tie the loose yarns, whether they are single yarns or bundles, into the fabric proper by interlocking in accordance 20 with my U. S. patent above referred to, a needle within the idling groups is selected for each such tie and separated out by a prearranged pattern setting at the same time the selection is made of the active needle groups; these "tie" needles by 25 special provision, as by special butt configuration, are advanced to an intermediate position when the active needles are moved to the fully advanced position, and thus will receive the loose yarns without casting the original loops or such loose 30 yarns which are held under the hook. The tie needles may thus be retracted and advanced simultaneously with the active needles without formation of loops and receive at each advancement a loose yarn. When a bundle has been formed 35 the "tie" needles will partake in the movements of the formerly idling needles with which they are grouped. Thus in the first movement to fully advanced position the tie needle will cast its original loop as well as the bundled yarns, and 40 the other needles of these groups will advance in front of the bundled yarns which are being held back by the sinker action and will cast 45 their loops; the next yarn thus will knit on all these needles, the loop on each tie needle passing down through the semi-loop formation of the 50 yarn bundle, and the yarn bundle thereafter passing on into the fabric interlocked within the interlooping portions of the original loop and the newly formed loop, as described for a single yarn in my above mentioned patent. Thereafter the 55 tie needles operate with their associated needles to form regular jersey stitches.

Fig. 28 represents in general the rear of a fabric like Fig. 8 with the loose yarns tied in as in Fig. 60 15 but with a further modification. Assuming the space between two vertical lines represents a wale, beginning at the left, there are five wales in which two types of yarn knit loops, then one type of yarn ceases forming loops and forms 65 bundles of loose yarns in the rear of the fabric for several wales lying behind regular loops of the second type of yarn and these bundles are shown at 230 and 231. Assume that the length of bundle 230 is ten wales or ten knitting needles 70 on a knitting machine and that the two middle needles of such a group are omitted or made inoperative. This would result in long unknit 75 needles of the second type in the front of the fabric corresponding to the two inoperative needles and this is indicated by the horizontal lines in the

front of bundles 230, 231. The fabric of Fig. 28 therefore has the previously described yarn bundles in the rear and non-bundled unknit 5 yarns for a definite distance in the front in the portion designated 232. The portion of the fabric to the right of portion 232 is the same construction as that to the left.

Fig. 29 is a modification of Fig. 28 and may comprise yarn of two colors in which one yarn predominates. For example yarn of the first 10 color may be fed to form eight successive rows in section 236 each row say seven wales wide after which only one yarn of the second color is fed and then again eight successive rows of the first color, 15 alternating in this manner. In section 236 the single fed yarn of the second color such as yarn 237 does not form loops but is carried in the rear of the fabric as in any of the previous figures. Then in section 238 each group of eight yarns of the first color is unknit but forms yarn bundles 20 in the rear of the fabric such as bundle 239 as in Fig. 16 or 17. If we assume that portion 238 is normally six wales wide or six needles wide it will be seen that each second color yarn such as 25 yarn 237 knits regular loops in only the first and sixth wales, the needles for the intervening four wales being inoperative so that in the said first and sixth wales long loops are formed and these long loops serve to tie into bundles the loose yarns of the first color crossing portion 238. The specified first and sixth wales are designated as 240 and 241. In between wales 240 and 241 each yarn of the second color since it is not knitted in the intervening wales is merged into each bundle such as bundle 239 until wale 241 is reached where it 30 is knitted to tie in the yarns of the first color before the said yarns of the first color start forming loops in several wales and rows in section 243. In this manner the cross yarns 232 of Fig. 28 are 35 eliminated and are incorporated in with the 40 bundles of yarn of the other type. The pattern effect of Fig. 29 is particularly striking due to the definite separation of the stripes of the predominating yarn such as stripes 236, 243. The 45 yarn of the so-called second color may of course be the same as the first color except treated differently in the knitting.

In the above description of the various figures it has been convenient to describe differently treated yarns as being of different colors. Such however is not essential as they may be different in some other characteristic such as texture, material or size,—silk or wool yarns, heavy and thin 50 yarns, etc. It is of course to be understood that if desired the differently treated yarns may have identical characteristics, the varied treatments merely giving a pattern effect in a fabric of a single color. For example it may be desirable to have Figs. 8 and 12 of a single color. It is also 55 to be understood that this invention is capable of embodiments, differing widely from those described above for illustrative purposes, without departing in any wise from the spirit of this invention as defined from the appended claims. 60

Certain of the subject matter disclosed herein is disclosed and claimed in a divisional application Ser. No. 756,741 filed Dec. 10, 1934.

What is claimed is:

1. A knitted fabric comprising yarn knitted into 70 loops in a plurality of wales and rows, one section of said fabric comprising a first yarn group knitted into regular front loops in more than two successive wales, a second yarn group knitted into regular front loops in more than two successive 75

wales in a second section of the fabric, a third 5
yarn group knitted into regular front loops in
more than two successive wales in a third section
of the fabric, where any mentioned group may
comprise only one yarn knitted in one row in a
given section, said sections being disposed across
the fabric parallel to a wale, said first yarn group
lying loosely behind the loops in said second and
third sections at least for a plurality of adjacent
10 wales without forming any front loops in said
second and third sections, said second yarn group
lying loosely behind the loops in said first and
third sections at least for a plurality of adjacent
wales without forming any front loops in said
15 first and third sections, said third yarn group
lying loosely behind the loops in said first and
second sections at least for a plurality of adjacent
wales without forming any front loops in said
first and second sections, a loose yarn of said first
20 yarn group in the rear of said second section be-
ing caught in the fabric in at least one wale of
said second section and being caught in the fabric
in at least one wale of said third section.

2. A knitted fabric comprising yarn knitted
25 into loops in a plurality of wales and rows, one
section of said fabric comprising a first yarn
group knitted into regular front loops in more
than two successive wales, a second yarn group
knitted into regular front loops in more than
30 two successive wales in a second section of the
fabric, a third yarn group knitted into regular
front loops in more than two successive wales in
a third section of the fabric, said sections being
disposed across the fabric parallel to a wale, said
35 third yarn group being followed by a fourth yarn
group knitted into front loops in said first sec-
tion, said fourth yarn group being followed by
a fifth yarn group knitted into front loops in
said second section, said fifth yarn group being
40 followed by a sixth yarn group knitted into loops
in said third section, where any mentioned group
may comprise only one yarn knitted in one row
in a given section, said first and fourth yarn
groups lying loosely behind the loops in said sec-
45 ond and third sections at least for a plurality of
adjacent wales without forming any front loops
in said second and third sections, said second and
fifth yarn groups lying loosely behind the loops
in said first and third sections at least for a
50 plurality of adjacent wales without forming any
front loops in said first and third sections, said
third and sixth yarn groups lying loosely behind
the loops in said first and second sections at
least for a plurality of adjacent wales without
55 forming front loops in said first and second sec-
tions, the loose yarns of said first and fourth
yarn groups in the rear of said second section
being caught in the fabric in a wale of said sec-
ond section and caught in the fabric in a wale
60 of said third section.

3. A knitted fabric in accordance with claim 2
in which the loose yarns of said first group and
the loose yarns of said second group in the rear
of said third section are caught together in the

fabric between loops in adjacent rows of one
wale of said third section.

4. A knitted fabric in accordance with claim 2
in which said first section is at least five wales
wide and the said second and third yarn groups
each comprises a single yarn which is caught in
the rear of said first section in one wale between
the same loops in adjacent rows.

5. A multicolor fabric of at least three colors,
yarns of one color forming loops in a plurality
10 of wales and rows in one section of the fabric,
yarns of a second color forming loops in a plu-
rality of wales and rows in a second section,
yarns of a third color forming loops in a plurality
15 of wales and rows in a third section, said sections
being disposed across the fabric parallel to a
row, said yarns of each color lying loosely be-
hind the loops of every other color at least for
a plurality of adjacent wales in those sections
20 where said each color forms no front loops, one
yarn of said first color and one yarn of said sec-
ond color being interlocked together in the rear
of the fabric in one wale of said third section
between loops of adjacent rows of the third color
25

6. A multicolor fabric of at least three colors,
one section comprising yarns of one color form-
ing regular front loops in a plurality of rows for
more than two successive wales, a second section
comprising yarns of a second color forming reg-
ular front loops in certain of said rows and for
30 more than two successive wales, yarns of a third
color forming regular front loops in certain of
said rows and for more than two successive wales,
the yarns of each color at least for a plurality of
35 adjacent wales lying loose in the back of said
fabric in those wales where another color yarn
forms loops, said loose yarns being interlocked
in the rear of the fabric at least once in each
color section.

7. A multicolor fabric in accordance with
claim 6 in which one yarn of said first color and
one yarn of said second color are interlocked to-
gether between adjacent loops in one wale of
40 said third color section.

8. A multicolor fabric of at least three colors
having one section comprising yarns of only one
color knitted into loops in a plurality of rows for
at least five wales, a second section comprising
yarns of only a second color knitted into loops
50 in certain of said plurality of rows for at least
five wales next to said first five wales, a third
color section comprising yarns of only a third
color knitted into loops in certain of said plu-
rality of rows for at least five wales next to said
55 second five wales, each yarn of each color lying
loosely behind the fabric for a majority of the
wales of the other colors but interlocked in the
rear of the fabric in at least one wale in each of
the other color section, said interlocking for each
60 specified yarn comprising being caught in the
rear of the fabric between the upper part of one
loop and the lower part of another loop in the
same wale.

VINCENT LOMBARDI. 65
